UNITED STATES PATENT OFFICE

2,031,132

MACHINE FOR CASTING STEREOTYPE PLATES AND THE LIKE

Karl Schäflein, Bern, Switzerland

Application September 21, 1933, Serial No. 690,414
In Germany November 11, 1932

1 Claim. (Cl. 22—2)

The invention relates to the drive for a machine for casting stereotype plates and for backing electrotypes of the kind set forth in my application 639,311. According to that application the opening and closing of the valve for controlling the flow of the molten metal into the mould, and all the movements of the mould, are carried out by means of a swinging toothed segment which is operated by cams and moves the valve direct by a connecting rod or the like, and the mould through a second toothed segment which it drives in known manner.

Now in order to provide all the drive parts in a smaller space, and, at the same time, to carry out the movements of the valve and mould in positive dependence one from the other, the present invention provides one swinging toothed segment each for opening and closing the control organ, on the one hand, and for closing and moving the mould against the pot, as well as for moving it away from the pot and opening it, on the other hand, and each of these segments is moved by a special cam.

On the drawing one construction of the invention is shown by way of example,

Fig. 1 being a side elevation of the drive, Fig. 2, a plan after removing the worm-wheel and

Fig. 3, a section through the worm-gearing and box taken along line 3—3 in Fig. 1.

By the motor *a* the worm *d* and worm-wheel *e* are driven through the friction or clutch coupling *c* which is put in and out of gear by means of the lever *b*. On both sides of the worm-wheel *e* there is a cam groove *f*, *g*, of which *f* serves to move the mould and *g* to open the valve. In the groove *f* engages a roller *h*, or the like, on a toothed segment *k* pivoted at *i*, and in the groove *g* engages a roller *l*, or the like, on the toothed segment *m*. The toothed segment *k* meshes continuously with the spur-wheel *n* and the toothed segment *m* with the spur-wheel *o*. With the spur-wheel *n* rotates the crank *p* which moves

the mould, while the crank *q* which moves the valve rotates with the spur-wheel *o*.

In one revolution of the worm-wheel *e* the mould and valve describe all movements necessary for one casting operation. In other words 5 the mould is closed by the cam *f*, toothed segment *k*, spur-wheel *n* and crank *p* and moved towards the pot, and the valve is opened by the cam *g*, toothed segment *m*, spur-wheel *o* and crank *q*. After some seconds the valve is 10 closed again through the agency of the same parts, whereupon the mould is moved away from the pot and opened. As soon as the mould is opened the tappet *r* on the actuating shaft *w* trips the lock *s* and releases the lever *b*, so that 15 the clutch *c* is put out of gear by the spring *t*.

The casing *u* incloses the gear with but little play. The worm *d* is arranged in the lower part of the casing, the upper part of the casing is arched in accordance with the worm-wheel and 20 the toothed segments are journaled in the side walls of the casing within the outline of the worm-wheel, so that the whole gear can be provided in a small casing containing an oil bath.

What I claim and desire to secure by Letters 25 Patent of the United States is:—

In a machine for casting stereotype plates or the like, having a mold and actuating means therefor, a metal supply valve and actuating means therefor, the combination of a drive for 30 said mold and valve, comprising power means, a worm driven by said power means, a clutch intermitted between said power means and said worm, a worm wheel meshing with said worm, a cam surface provided on each side of said worm 35 wheel, gear means mounted within the periphery and on each side of said worm wheel and cooperating with said cam surfaces, and gears meshing with said gear means and arranged to transmit motion of the latter to said operating means for 40 the purpose of actuating said mold and valve.

KARL SCHÄFLEIN.
